SURVEYOR'S CHAIN CLAMP OR SIMILAR ARTICLE

Julius H. Smith, Rte. 2, Molena, Ga. 30258

Filed Aug. 4, 1967, Ser. No. 8,135

Term of patent 14 years

(Cl. D54—13)

FIG. 1 is a perspective view of a surveyor's chain clamp or similar article showing the novel design;

FIG. 2 is a side elevational view looking at the side opposite that shown in FIGURE 1;

FIG. 3 is a top plan view of FIG. 1;

FIG. 4 is a bottom plan view of FIG. 1;

FIG. 5 is an end elevational view looking from left to right at FIG. 2; and

FIG. 6 is an end elevational view looking from right to left at FIG. 2.

I claim:

The ornamental design for a surveyor's chain clamp or similar article, as shown.
